UNITED STATES PATENT OFFICE.

SARPALA MARTIN, OF MARQUETTE, MICHIGAN.

TRUNK-LOCK.

1,090,736.

Specification of Letters Patent. Patented Mar. 17, 1914.

Application filed September 10, 1913. Serial No. 789,218.

To all whom it may concern:

Be it known that I, SARPALA MARTIN, a subject of the Czar of Russia, residing at Marquette, in the county of Marquette and 5 State of Michigan, have invented new and useful Improvements in Trunk-Locks, of which the following is a specification.

This invention relates to certain new and useful improvements in locks, the primary 10 object of the invention being to provide a lock which is simple of construction, reliable and efficient in action, and which can only be operated in a determined manner and by a special form of key.

15 A further object of the invention is to provide a double swinging bolt lock of the character described, in which springs are provided for holding the bolts normally projected and locking them against releasing movement, combined with tumblers for retracting the springs to permit the bolts to be actuated.

20 The invention consists of the features of construction, combination and arrangement 25 of parts hereinafter fully described and claimed, reference being had to the accompanying drawings, in which:—

Figure 1 is a perspective view of a lock constructed in accordance with my invention. Fig. 2 is a vertical longitudinal section through the lock taken on a line between the locking bolts and keyhole plate. Fig. 3 is a similar view taken on a line between the back plate of the lock casing 35 and the tumblers. Fig. 4 is a horizontal longitudinal section on the line 4—4 of Fig. 2. Figs. 5 and 6 are vertical transverse sections on the line 5—5 of Fig. 2 looking in opposite directions. Fig. 7 is a perspective 40 view of a form of key which may be used in connection with the lock, showing the movable bit retracted. Fig. 8 is a longitudinal section through the key showing in full and dotted lines the movable bit retracted and 45 projected.

In carrying my invention into practice I provide a lock casing including a back plate 1 and a keyhole plate 2, said casing being provided with a pair of spaced openings 3 for the entrance and exit of the keepers, which may be of any suitable construction. The plate 2 is provided with a keyhole 4 of ordinary form, and the plate 1 with a keyhole 5 to receive the outer end of the stem of 50 the key when fully inserted. Extending between the said plates 1 and 2 are spaced

pins 6 and 7, which are arranged in horizontal alinement with each other and above the plane of the said keyhole 4 and opening 5. Supported by these pins 6 and 7 is an intermediate key guiding or partition plate 8 having a keyhole 9 corresponding to and arranged in alinement with the keyhole 4.

Pivoted supported by the pins 6 and 7 are locking bolts 10 and 11, which bolts are 65 vertically disposed and pivoted at an intermediate point between their ends to swing toward each other for a releasing action and away from each other for a locking action.

The upper ends of the bolts are provided 70 with outwardly projecting locking hooks 12 for engagement with the keepers, and said bolts are respectively provided below the pivot pins 6 and 7 with beveled and straight surfaces 13 and 14 adapted to be engaged by 75

the bits of a double-bitted key to spread the lower ends of the bolts and thus move their hook ends 12 inwardly to a releasing position. The bolts are provided at the lower ends of their outer edges with stop lugs or 80

projections 14' which are arranged in the path of the laterally bent ends 15 of locking and releasing springs 16, said springs being secured at their upper or opposite ends by 85

screws or other similar fastenings 17 to the casing. The springs 16 are movable toward and from the side edges of the partition plate in a direction longitudinally of the casing, and their ends 15 are arranged in the path of outward movement of the shoulders 90

14 of the locking bolts. As the lower ends of the locking bolts are movable on arcs at an angle to the line of yielding motion of the springs, it is apparent that the 95

springs normally lock the lower ends of the bolts against outward movement, thus maintaining the hooked ends of the bolts normally in locking position. After actuation 100

of the lock and removal of the key, the springs also serve to return the bolts to 100

normal locking position, thus rendering them self-acting in this connection.

Pivoted mounted upon the pins 6 and 7 between the partition plate 8 and back plate 1 of the casing are tumblers 18 and 19 for 105 coaction with the respective bolts 10 and 11. The bolts and tumblers are loosely mounted on the pins 6 and 7 and the tumblers are movable in planes parallel with the path of movement of the bolts. The tumbler 18 is provided with a beveled surface 110 and the tumbler 19 with a straight or

slightly curved surface 21 for coaction with sections of the bits of a double-bitted key, whereby said tumblers may be swung outwardly. The outer edges of the tumblers 5 are disposed in line with and normally engaged by the ends 15 of the springs 16, whereby the tumblers are normally maintained with the bolts in retracted position and are so arranged that upon the outward 10 swinging movements of the lower ends of the tumblers, the springs will be forced outwardly beyond the paths of the shoulders 14, thus permitting the locking bolts to be moved to unlocking or releasing position. 15 The upper ends of the tumblers are provided at their inner edges with stop shoulders or projections 22 normally engaged by shoulders 23 on the bolts, whereby the tumblers normally coöperate with the springs to hold the bolts from releasing movement. 20 The shoulders 23 are adapted to engage stop shoulders 24 formed on the upper edge of the partition plate 8, whereby the outward swinging movement of the hooked ends of 25 the bolts is limited.

It will be understood from the foregoing description that in order to retract the locking bolts it is necessary to employ a key having diametrically disposed bits bifurcated to 30 provide engaging projections for action on opposite sides of the partition plate 8 to simultaneously engage the bit engaging surfaces of the two sets of bolts and tumblers. In Figs. 7 and 8 I have shown a form of key 35 25 which may be employed. This key has a round shank or stem 26 of a size to fit the round portions of the slots 4 and 9 and the opening 5 and provided with oppositely disposed bifurcated bits 27 and 28. The bit 27 40 is fixed or rigid with the stem, while the bit 28 is adapted to normally lie within a recess 29, so as to allow the key to be inserted through the slots 4 and 9, and to be projected outwardly when the key is so inserted, so that the divided portions of the 45 respective bits will be disposed on opposite sides of the plate 8 in position to engage the bit engaging surfaces of the bolts and tumblers, so that upon turning the key to the left 50 the lower ends of the tumblers and bolts will be forced outwardly. By this means the springs 16 will be moved out of the paths of the stop shoulders at the lower ends of the bolts, thus permitting the hooked upper 55 ends of the bolts to be swung inwardly to releasing position. When the key is turned back to normal position and removed, the pressure of the springs upon the tumblers and bolts will automatically return the same 60 to normal or locking position.

For the purpose of projecting and retracting the bit 28, said bit is mounted upon the outer or free end of an arm 30 pivoted adjacent its inner end upon a pin 31, said arm 65 being arranged in a normally inclined posi-

tion for movement within a slot 32 communicating with the recess 29. The arm is adapted to be engaged by a controlling member 33 connected with a finger piece 34 movable in a guide slot 35 in the finger piece 70 of the key, said member 33 being adapted to slide in contact with the shank to positions on opposite sides of the line of the pivot 31 whereby the shank may be tilted to project or retract the bit 28 as will be readily understood. Hence it will be seen that the key must be inserted with the bit 28 retracted in order to pass through the keyholes 4 and 9, and that the bit 28 must then be projected in order to provide the required number of 75 engaging surfaces for coaction with the tumblers and bolts. While, of course, the keyholes 4 and 9 may be of the required shape for the passage of a double-bitted key having fixed bits, the construction described is 80 preferred, as it requires the use of a special form and mode of operation of the key in order to actuate the lock, whereby additional security is obtained. 85

I claim:

1. A lock including a pivoted locking bolt, a releasing tumbler movable in the same direction as the bolt, and a spring normally holding the bolt from movement and movable by said releasing tumbler in a direction 90 away from the bolt and at an angle to its swinging movement for releasing said bolt. 95
 2. A lock including a pivoted bolt having a locking shoulder at one end and a keeper engaging member at its opposite end, a releasing tumbler movable in the same direction as the bolt, and a spring adapted to engage and retain the bolt and tumbler in normal position and lying in the path of said locking shoulder to normally lock the bolt 100 from movement, said spring being adapted to be released and moved out of the path of movement of the bolt by the action of the tumbler. 105
 3. A lock including a casing having a keyhole therein, a partition plate arranged within and spaced from the walls of the casing and having a keyhole registering with the keyhole therein, locking bolts pivotally mounted upon one side of said partition plate and on opposite sides of the keyhole therein, releasing tumblers mounted upon the opposite side of the keyhole plate in line with the respective tumblers, said bolts and tumblers being adapted to be engaged and simultaneously operated by a double-bitted key, and springs for normally locking the bolts from releasing movement and adapted to be moved out of the paths of the bolts by the action of the tumblers. 110 115
 4. A lock including a casing having a keyhole therein, a partition plate disposed within the casing between the walls thereof and provided with a similar keyhole, pivoted locking bolts upon one side of said plate, 120 125

130

said bolts having keeper engaging members at one end and locking shoulders at their opposite ends, tumblers pivotally mounted upon the opposite side of the keeper plate in line with the bolts and movable in paths parallel with the bolts, coacting surfaces upon the tumblers and key engaging ends of the bolts to hold such ends of the bolts from releasing movement, and springs arranged to engage and hold the tumblers and bolts normally retracted, said springs being ar-

ranged to lie in the paths of movement of the locking shoulders of the bolts to lock said bolts from movement and to be moved out of the paths of movement of said locking shoulders by the action of the tumblers. 15

In testimony whereof I affix my signature in presence of two witnesses.

SARPALA MARTIN.
